US0D1109438S

(12) **United States Design Patent** (10) **Patent No.:** **US D1,109,438 S**
(45) **Date of Patent:** **** Jan. 13, 2026**

(54) **HELMET**

(71) Applicant: **Specialized Bicycle Components, Inc.**,
Morgan Hill, CA (US)

(72) Inventors: **Luiz Felipe de Melo Dias**, Minas
Gerais (BR); **Allen Albert**
Bischofberger, Ben Lomond, CA (US);
Alexander Hart Jerome, Morgan Hill,
CA (US); **Katherine Lynn**
Martonchik, Northfield, OH (US);
David Tyler Debus, Felton, CA (US);
Franklyn Yuri Souza Shimizu, Sao
Paulo (BR); **Christopher Thomas**
Pietrzak, Redwood City, CA (US)

(73) Assignee: **Specialized Bicycle Components, Inc.**,
Morgan Hill, CA (US)

(**) Term: **15 Years**

(21) Appl. No.: **29/965,011**

(22) Filed: **Sep. 25, 2024**

Related U.S. Application Data

(63) Continuation of application No. 29/829,387, filed on
Mar. 4, 2022, now Pat. No. Des. 1,050,611.

(51) **LOC (15) Cl.** **02-03**

(52) **U.S. Cl.** **D29/102**

(57) **CLAIM**

The ornamental design for a helmet, as shown and
described.

DESCRIPTION

FIG. 1 is an isometric view of a top, front, and right side of
a helmet, showing our new design;
FIG. 2 is an isometric view of a top, front, and left side of
the helmet of FIG. 1;
FIG. 3 is an isometric view of a top, rear, and left side of the
helmet of FIG. 1;
FIG. 4 is an isometric view of a top, rear, and right side of
the helmet of FIG. 1;
FIG. 5 is a front elevational view of the helmet of FIG. 1;
FIG. 6 is a rear elevational view of the helmet of FIG. 1;
FIG. 7 is a right side elevational view of the helmet of FIG.
1;
FIG. 8 is a left side elevational view of the helmet of FIG.
1;
FIG. 9 is a top plan view of the helmet of FIG. 1; and,
FIG. 10 is a bottom plan view of the helmet of FIG. 1.
The dash-dash-dash broken lines illustrate portions of the
helmet that form no part of the claimed design.

1 Claim, 10 Drawing Sheets
